(57) **CLAIM**

The ornamental design for a meat injector kit, as shown and described.

DESCRIPTION

FIG. 1 depicts a front view of the meat injector, shown separately from the rest of the kit for clarity of the disclosure.

FIG. 2 depicts a top view of the meat injector shown in FIG. 1.

FIG. 3 depicts a left side view of the meat injector shown in FIG. 1.

FIG. 4 depicts a right side view of the meat injector shown in FIG. 1.

FIG. 5 depicts a perspective view of the meat injector shown in FIG. 1.

FIG. 6 depicts a perspective view of the needles and pipe-cleaners included in the meat injector kit, shown separately from the meat injector for clarity of the disclosure.

FIG. 7 depicts a perspective view of the meat injector shown in FIG. 1 attached to one of the needles included in the meat injector kit for clarity of the disclosure.

FIG. 8 depicts an exploded perspective view of the meat injector shown in FIG. 1 and one of needles included in the meat injector kit for clarity of the disclosure; and,

FIG. 9 depicts all constituent elements of the meat injector kit as depicted in FIGS. 1-8.

1 Claim, 8 Drawing Sheets
